(57) CLAIM

The ornamental design for a floor mat, as shown and described.

DESCRIPTION

FIG. 1 is a top perspective view of a floor mat according to our design;

FIG. 2 is a top view thereof;

FIG. 3 is a left side thereof;

FIG. 4 is a right side view thereof;

FIG. 5 is a back side view thereof;

FIG. 6 is a front side view thereof;

FIG. 7 is a sectional view taken along Line 7-7 of FIG. 2; and,

FIG. 8 is a sectional view taken along Line 8-8 of FIG. 2. The bottom of the floor mat is unadorned and forms no portion of the claimed design. The broken lines shown illustrate environment that forms no part of the claimed design.
